COMBINED VISE AND TELESCOPING STAND FOR PIPE WORK

Marion L. Ewing and Orison P. Kambestad, Sacramento, Calif., assignors to Kambestad-Ewing, Inc., Sacramento County, Calif.

Application November 9, 1953, Serial No. 27,497

Term of patent 3½ years

(Cl. D54—14)

FIG. 1

FIG. 2

Figure 1 is a perspective view of the combined vise and telescoping stand for pipe work, showing our new design.

Figure 2 is a side elevational view thereof.

We claim:

The ornamental design for a combined vise and telescoping stand for pipe work, substantially as shown.
